Attorney

UNITED STATES PATENT OFFICE.

VIRGIL REA STRADER, OF PHILIPPI, WEST VIRGINIA.

SUSPENDERS.

1,388,213.

Specification of Letters Patent. Patented Aug. 23, 1921.

Application filed March 17, 1921. Serial No. 452,926.

To all whom it may concern:

Be it known that I, VIRGIL REA STRADER, a citizen of the United States of America, and resident of Philippi, county of Barbour, 5 and State of West Virginia, have invented certain new and useful Improvements in Suspenders, of which the following is a specification.

This invention relates broadly to garment supporters, and more specifically to an end structure for suspenders.

The main object of the invention is to simplify and structurally improve the suspender-end structure disclosed in my prior 15 Patent No. 1,356,944, granted to me October 26, 1920.

The structure shown in the patent mentioned includes a looped cord having its ends projected through eyes provided 20 therefor in a spring-overlying yoke, and clamps attached to said ends and disposed in seated relation to said yoke. An objectionable feature of said structure resides in the employment of the clamps, due to the 25 fact that they become detached more or less readily by strains imposed thereon through pulls on the cord.

The chief aim of the present invention is to obviate the objection referred to by the 30 provision of a suspended end in which both the yoke and clamps of my said prior structure are dispensed with.

With this and other objects in view, the invention resides in the features of construction and arrangement of parts which 35 will hereinafter be fully described, reference being had to the accompanying drawings, in which—

Figure 1 is a sectional elevation of a suspender end constructed in accordance with 40 my invention, and—

Fig. 2 is an enlarged section on line 2—2, Fig. 1.

Referring to said drawings, 1 indicates a 45 pocket formed by doubling the end portion of a suspender strap 2 of inelastic webbing back upon itself and stitching the same along its lateral edges and across its end to the underlying strap.

Seated at the bottom of the pocket is the 50 lower end of a spring 3 formed of a narrow strip of resilient steel bent into zigzag shape and having its upper end located adjacent to the upper end of said pocket.

Looped over the top end of said spring is

an intermediate portion of a cord 4 which extends thence downward on opposite lateral sides of said spring and outward through eyes 5 provided therefor in the bottom of said pocket.

The longer of the end portions of the cord projecting outward through said eyes 5 is turned back upon itself to form a lower terminal loop or button-receiving portion 4^a, and the two ends of the cord are brought 65 together, or into meeting relation, within the embrace of a metal clamp 6 which is disposed in rigidly binding or clamping relation to the two substantially parallel members of the cord above said button-receiving 70 loop.

The topmost lap 3^a of the spring 3 is horizontally disposed and is preferably slightly concavo-convex in cross section to afford a seat for the overlying portion of the cord. 75 the latter being firmly attached to said lap 3^a by means of a clamp 7.

The spring 3 yields readily to compression strains imposed thereon through pulls applied to the cord 4, thus permitting relative downward movement of the latter with respect to the inelastic strap 2.

As is obvious, the construction described is equally adapted to be embodied in suspenders and garment supporters of the different types or forms commonly employed 85 by men, women and children.

What is claimed is—

1. A suspender comprising an inelastic webbing doubled upon itself to form a 90 pocket, a zigzag spring disposed within said pocket and having its lower end seated upon the bottom of the latter, a cord having an intermediate portion thereof supported upon the upper end of said spring, said cord having the opposite members thereof located laterally of said spring and projected outwardly through the bottom of said pocket, a clamp whereby said intermediate portion of the cord and the supporting portion of the 95 spring are firmly attached together, and means uniting the opposite ends of said cord outside said pocket and forming a terminal loop.

2. A suspender comprising an inelastic 105 webbing doubled upon itself to form a pocket, a zigzag spring disposed within said pocket and having its lower end seated upon the bottom of the latter, the topmost lap of said spring being disposed horizontally, a 110

cord having an intermediate portion thereof seated upon said topmost lap and extending thence downwardly between the sides of said spring and the lateral edge portions of said 5 pocket and protruding through the bottom of the latter, a clamp securing said cord in its said seated position, and means uniting the ends of said cord outside said pocket and

forming means for attaching said cord to a garment.

In testimony whereof, I affix my signature in presence of two subscribing witnesses.

VIRGIL REA STRADER.
